UNITED STATES PATENT OFFICE.

JAY M. JOHNSON, OF CHICAGO, ILLINOIS.

TICKET-CANCELING AND COIN FARE-BOX.

1,253,980.

Specification of Letters Patent. Patented Jan. 15, 1918.

Application filed May 28, 1914. Serial No. 841,686.

To all whom it may concern:

Be it known that I, JAY M. JOHNSON, a citizen of the United States, and a resident of the city of Chicago, in the county of Cook and State of Illinois, have invented certain new and useful Improvements in Ticket-Canceling and Coin Fare-Boxes; and I do hereby declare that the following is a full, clear, and exact description of the same, reference being had to the accompanying drawings, and to the numerals of reference marked thereon, which form a part of this specification.

It has become nearly general in practice for street railway companies and certain other transportation lines, and even places of amusement of certain kinds, to make use of collection boxes operated by the fare or ticket taker, and into which tickets and sometimes cash fares, are delivered indiscriminately mixed, as the same are received. Usually, such boxes are mere receptacles to receive the fare or prepayment and it is possible, should the operator or any one else have access to the tickets, to use the tickets again for payment of fare or admission. In some instances where tickets only are collected, a ticket chopper is used, which cuts up the tickets or macerates them beyond the possibility of use or even recognition and identification.

It is an object of this invention to afford a fare box adapted to receive coin fare and to deliver the same to an inspection compartment, and to afford in connection therewith a ticket canceling mechanism through which the tickets are delivered to a place or compartment for inspection.

It is also an object of the invention to afford a self-inking canceling device.

It is further an object of the invention to afford a device whereby the normally inert canceling device, is brought into operation by the presentation of the tickets thereinto.

It is an important object of the invention to afford a construction whereby the ticket is canceled without mutilation, thus enabling the auditor to inspect and identify the tickets canceled.

It is an important object of the invention to afford a fare box adapted for use in collecting both cash fares and ticket fares; to deliver the one to a place not accessible to the operator except for inspection; to cancel the tickets, and to deliver the same for inspection to a compartment not accessible to

the operator, and to afford means to deliver the inspected tickets to a locked collection compartment.

The invention embraces many novel features, and (in a preferred form) is illustrated in the drawings and hereinafter more fully described.

In the drawings:

Figure 1 is a front elevation partly in section of a device embodying my invention.

Fig. 2 is an enlarged section on line 2-2 of Fig. 1.

Fig. 3 is a front interior view of the back of the casing and of the baffle plates thereon affording a part of the tortuous coin chute.

Fig. 4 is an enlarged, fragmentary front elevation with the front plate removed.

Fig. 5 is an enlarged, fragmentary top plan view showing the front plate of the casing, and the cap for the coin chute removed.

Fig. 6 is an enlarged, fragmentary detail illustrating the construction of the ticket slot.

Fig. 7 is a fragmentary section on line 7-7 of Fig. 4.

Fig. 8 is an enlarged, longitudinal section of the canceling, and one of the inking rolls.

Fig. 9 is a diagrammatic detail illustrating the motor circuit and switch.

Fig. 10 is an enlarged detail view illustrating the drive for the canceling rolls.

Fig. 11 is a detail view of the spring construction for closing and supporting the bottom of the ticket inspection compartment.

Fig. 12 is a reduced vertical section, illustrating the driving of the device from the motor of the fare register with which the device is associated.

Figs. 13 and 14, are enlarged details of the drive illustrated in Fig. 12.

As shown in the drawings:

A casing is constructed of cast or pressed metal or any suitable material, substantially identical in most particulars with the casing illustrated and described in our co-pending application for "ticket and coin fare boxes", filed May 28, 1914, Serial Number 841,685.

As shown, said casing comprises side walls 1, a back wall 2, an intermediate partition 105 3 and a front wall 4, affording a rear coin chute and a front ticket canceling device, an inspection compartment, and a collection compartment.

As shown, the back plate 2, has secured thereto central upwardly directed baffle plates 5, lateral inwardly and down-

wardly directed baffle plates 6, a lower central angular baffle plate 7, and lower baffle plates 8, corresponding with the baffle plates 6, before described, which are of a 5 width to extend across the space between the back plate 2, and the partition 3, and from which the coin fares inserted through the coin apertures in the cap 9, fall successively from one to another until at last delivered 10 into the coin inspection compartment 10. Said compartment 10, as shown, is provided with glass or other transparent sides 11, mounted in a suitable metallic frame 12, and which is secured upon, and 15 is the collecting means for a fare register 13, as illustrated in Figs. 1 and 12, said coins falling upon a dumping door or bottom upon which the same are supported until delivered to the fare registering 20 machine.

The front, back and side walls of the casing above described, are provided near their lower ends with downwardly facing shoulders 14, below which the casing is 25 restricted in width and thickness to fit into the coin inspection compartment before described, as illustrated in Figs. 1 and 2, and is rigidly secured therein by means of any suitable bolts or otherwise to prevent removal 30 except by those authorized so to do. A permanent floor or bottom 15, is provided at the bottom of the side walls 1, and said partition 3, of the casing, upon which the canceled and inspected tickets fall, said 35 bottom 15, affording the bottom of the collection compartment. A door 16, is suitably hinged to the front wall 4, and provided with a lock 17, permitting the canceled and inspected tickets to be removed by one 40 possessed of the required key.

Above the collection compartment, is the inspection compartment for the ticket fare box, and above the latter and delivering thereinto, are the canceling means.

45 Said canceling means comprise tubular rolls or shafts 18, having threaded plugs 19, in each end thereof and adapted to contain printers' ink or any suitable staining or discoloring means capable of canceling the 50 ticket by marking the face thereof. Secured on said shafts are bushings or collars 20, each provided with a peripheral flange and engaged on opposite sides of a felt washer or roll 21, as shown more fully in Fig. 8, and 55 as shown, the tubular shaft is perforated at each of said felt washers 21, to permit the ink contained in said shaft to be absorbed thereby. Intermeshing gear wheels 22, are provided on said shafts to drive the same 60 simultaneously and oppositely.

65 Mounted in a suitable casing 23, which, if preferred, may be secured to the side wall of the fare box, is an electric motor, the shaft 24, of which is provided with a pinion 25, as shown in dotted lines in Fig. 10, and

which meshes with a relatively large gear 26, to which is rigidly secured a coaxial pinion 27, which meshes with one of the gear wheels 22, on one of said shafts, so that the drive of the motor greatly reduced in speed, is communicated to rotate said canceling rolls. One of said rolls is journaled at its ends in slotted apertures in the bearing plates 23^b and 24^b, which form a supporting frame therefor, as shown in 70 Figs. 2, 10 and 11, and leaf springs 26^a and 27^a, are suitably engaged on said frame plates and bear in any suitable manner against said adjustable shaft or the gear thereon, as illustrated, and act to hold said 75 shifting roll lightly inwardly.

The front wall of the casing inclines upwardly and rearwardly and over the canceling inking rolls, as before described, as 80 shown in Fig. 2, and is provided with a 85 ticket slot, the sides 28 and 29, of said slot inclining inwardly and downwardly toward the point of contact between the felt washers of the canceling rolls, as shown in Fig. 2. As shown, a metal plate 30, is secured 90 upon suitable lugs 31, which may be integral with the front plate, and as shown in Fig. 2, extends outwardly and downwardly through the ticket slot in the front wall of the casing, and is provided with a restricted 95 slot coinciding with the ticket slot in the front wall of the casing.

As shown in Figs. 1 and 6, the front wall of the casing above the slot, is provided with downwardly directed ribs or teeth 33, 100 which extend into the ticket slot, and the edges of the slot in said plate 30, is provided with projections or teeth registering therewith and acting to restrict the ticket slot to prevent any object other than a ticket 105 to be inserted therethrough.

Means are provided for completing the motor circuit by the insertion of the ticket through the ticket slot. For this purpose, as shown more fully in Figs. 2 and 7, a rock 110 shaft 34, is journaled at its ends in the frame plates 23^b, and 24^b, and secured thereon is an arm 35, which extends downwardly therefrom and to which is engaged a switch bar 36, which, as illustrated diagrammatically in Fig. 9, controls the motor circuit. Secured on the partition 3, adjacent the switch bar, is a contact member 36^a, whereon the switch bar closes in completing the 115 motor circuit.

Extending forwardly from the rock shaft 34, and over the adjacent canceling and inking rolls, are fingers 37, which extend to a point between the rolls and into position to be engaged and depressed when the ticket is 120 inserted. Secured on the front plate of the machine, are corresponding fingers 38, which direct the inserted end of the ticket against the fingers 37, as illustrated in Fig. 2. 125

When the ticket is inserted, the rock shaft is actuated to close the switch immediately energizing the motor and driving the inking rolls and the inserted ticket engaged by the 5 inked felt washers, is drawn therethrough, each of the felt washers marking an inked line thereon spaced a sufficient distance apart to enable the ticket to be identified by examination.

10 Journaled in the frame plates 23^b and 24^b, is a shaft 39, which is below the canceling rolls and adjacent the rear partition 3. Secured thereon and inclining downwardly and forwardly is a plate 40, which affords the 15 floor of the inspection compartment. Secured on one end of said plate and extending through a slot in the frame plate 23^b, is a pin 41, and engaged thereon at the outer side of the side wall of the casing is a lever 20 42, adapted for manual actuation to swing said plate 40, downwardly, permitting the canceled and inspected tickets to fall into the ticket collection compartment.

As shown, said plate 40, is normally supported, as shown in Figs. 2 and 11, by the spring 26^a, which is the same spring whereby the adjustable canceling shaft is yieldingly held in operative position. This spring, at its upper end, as shown, bears 30 against said shaft, and against a suitable stud 42^a, secured on the frame plate 23^b, and at its lower end engages behind the pin or arm 41, as illustrated in Fig. 11.

As shown a plate 43, is secured on the 35 front wall of the casing and extends rearwardly and downwardly into position to afford a stop for the lower end of the plate 40, and against which the lower end of the plate 40, normally rests under the impulse of its 40 spring 26^a, before described.

A plate of glass 44, is set in a suitable aperture in the front wall above said plate 43, to permit ready inspection of the canceled tickets supported upon the plate 40, as 45 before described.

The operation is as follows:

The coins when inserted in the coin apertures in the cap 9, fall by gravity from one baffle plate to another following a tortuous 50 passage, and to the compartment 10, from whence (if mounted in connection with the registering fare box) they may be dumped into the hopper of the fare box for further operation. When the ticket is presented for 55 fare, it is inserted into the ticket slot, thereby closing the switch for the motor by actuating the fingers or arms 37, downwardly. The ticket is immediately seized by the felt washers on the inking rolls and drawn there- 60 between, canceled by inked lines on both sides thereof, and dropped upon the floor or plate 40, for inspection, the inclined position of said plate admirably supporting the tickets in full view of the operator and the 65 public. When the ticket has been inspected,

the lever 42, is tripped, permitting the ticket to fall into the collection compartment. Of course, upon the fall of the ticket from the canceling rolls, the switch bar springs out of contact, and the motor circuit is broken. 70

Of course, when the device is assembled in connection with a registering fare box, which is itself driven by a motor, as is frequently the case, the canceling devices may be operated by the same motor that operates 75 the fare register. Such a connection is illustrated in Figs. 12 and 13, in which the fare register 13, is provided with a motor 48, from whence a shaft 49, is driven through the medium of a belt or sprocket chain 50, 80 or in any suitable manner, and this may drive by means of suitable intermeshing bevel gears carried upon suitable shafts 51, 52, 53, with the pinion 54, for driving the gear train before described. 85

Of course, if preferred, and perhaps more economically, the drive from the motor 48, to the train for the canceling rolls, may be effected by means of a flexible shaft or any of the well known or usual gears of power 90 transmission. Obviously numerous details of the construction and operation and drive may be varied without departing from the principles of this invention. I have shown but a preferred form for the canceling mechanism embodying my invention, and I therefore do not purpose limiting the patent granted otherwise than necessitated by the prior art. 95

I claim as my invention: 100

1. A device of the class described embracing a casing, a slot therein to receive the tickets, rotative inking means, fingered rocker means to receive said tickets to pass the same between said inking means, a 105 switch arm on said rocker means to be actuated therewith by the insertion of said tickets through said slot to operate said inking means to deliver the tickets therethrough, an inspection compartment to 110 which the tickets are delivered by the inking means, a spring supported bottom for said inspection compartment, and manually operated means for tripping the same to deliver the tickets to a place of deposit. 115

2. In a device of the class described embracing a casing, a ticket slot therein, inking rolls in said casing, rocker means for receiving a ticket from said slot to pass the same between said inking rolls, means acting to yieldably hold one of said inking rolls in position, an electric circuit in said casing, and a switch arm connected to said rocker means adapted to close said circuit when a ticket is inserted through said slot 120 to depress said rocker means thereby operating said inking rolls to deliver the ticket between said inking rolls to a place of deposit. 125

3. In a device of the class described a cas- 130

- ing, a ticket slot therein, inking mechanisms positioned adjacent said slot, fingered means movably mounted thereabove and projecting therebetween to receive the ticket from said slot and pass the same between said inking mechanisms, one of said inking mechanisms yieldably mounted to permit passage of the ticket between said mechanisms, and contact means connected to and set in operation by said fingered means by the insertion of said ticket through said slot to drive said inking mechanisms to deliver the ticket therethrough to a place of deposit.
4. In a device of the class described a casing, a ticket slot therein, inking rollers mounted adjacent the ticket slot, fingered rocker means thereabove to receive a ticket inserted through said slot and pass the same between said rollers, one of said rollers yieldably mounted to permit passage of said ticket between said rollers, driving means for said rollers to deliver the ticket therethrough, an arm connected with said rocker means, and an electric switch adapted to be moved to closed position by said arm when said ticket is inserted through said slot to depress said rocker means to operate said driving means for said rollers.
5. A device of the class described a casing having a restricted ticket slot therein, motor driven inking rolls journaled adjacent the ticket slot to engage the ticket inserted, and to draw the same therebetween and to a place of deposit, and pivotally mounted fingers extending downwardly between said rolls operated by the insertion of the ticket for starting the rolls in operation.
6. In a device of the class described a casing, canceling inking rolls, a motor to drive the same, a motor circuit and switch, and

means for closing the motor circuit to drive said rolls by presentation of a ticket or the like to the inking rolls, said means comprising a rock shaft journaled in said casing, finger members mounted thereon and extending to a point between said rolls, and a switch arm on said rock shaft adapted to close said motor switch when said finger members are depressed by the insertion of 50 tickets.

7. A device of the class described embracing a ticket canceling fare box, embracing a casing, a ticket slot therein, a pair of inking rolls journaled to receive the ticket 55 therebetween when inserted in the ticket slot to ink both sides of the ticket simultaneously, a motor entrained to drive said rolls, fingered rocking means associated with said rolls, and a switch operated thereby when 60 a ticket is inserted to depress said fingered rocking means for energizing the motor, and thereby delivering the ticket through the rolls.

8. In a device of the class described embracing a ticket canceling fare box including normally inert canceling means, an inspection box beyond the same, co-acting fingered means mounted above said canceling means, an arm connected therewith 70 whereby the ticket presented to the canceling means acts to move said arm to energize the canceling means to cancel the ticket and deliver the same thereby to the inspection compartment.

In testimony whereof I have hereunto subscribed my name in the presence of two subscribing witnesses.

JAY M. JOHNSON.
